(57) **CLAIM**

The ornamental design for a power generator for surgical hand pieces, as shown and described.

DESCRIPTION

FIG. 1 is a perspective view of a power generator for surgical hand pieces showing our new design;

FIG. 2 is a front view of the power generator for surgical hand pieces;

FIG. 3 is a first side view of the power generator for surgical hand pieces;

FIG. 4 is a second side view of the power generator for surgical hand pieces;

FIG. 5 is a back view of the power generator for surgical hand pieces;

FIG. 6 is a top view of the power generator for surgical hand pieces; and,

FIG. 7 is a bottom view of the power generator for surgical hand pieces.

In the drawings, the broken lines are for the purpose of illustrating environment only and form no part of the claimed design.
